Otto Seemüller

By Attorneys

UNITED STATES PATENT OFFICE.

OTTO SEEMULLER, OF DETROIT, MICHIGAN.

AIR-GUN.

1,327,064.

Specification of Letters Patent.

Patented Jan. 6, 1920.

Application filed June 13, 1919. Serial No. 303,892.

To all whom it may concern:

Be it known that I, OTTO SEEMULLER, a citizen of the United States of America, residing at Detroit, in the county of Wayne 5 and State of Michigan, have invented certain new and useful Improvements in Air-Guns, of which the following is a specification, reference being had therein to the accompanying drawings.

- 10 The primary object of my invention is to provide an air gun embodying positive and reliable means, in a manner as herein-after set forth, for utilizing air placed under pressure as the propulsion means of a projectile, said means including a piston which is manually retracted and adapted to be projected by the expansive force of a spring placed under tension during the manual retraction of the piston.
- 20 Another object of this invention is to provide a novel arrangement of levers by which the piston of an air gun may be retracted in synchronism with the placing of a spring under tension, the levers being articulated 25 so that the operator of the gun may easily and quickly cock or set the same.

A further object of my invention is to furnish an air gun with a pivoted barrel which is swung to one side of the breach 30 piece of the gun in order that a projectile may be placed in the barrel, the projectile as well as the manner of loading the gun being in contradistinction to a barrel adapted to have a shot placed in the outer end 35 thereof.

A still further object of my invention is to provide an air gun which includes a novel sear construction, means for adjusting the tension of the spring of the gun, and certain other novel constructions which will 40 be hereinafter specifically described and then claimed.

Reference will now be had to the drawings, wherein—

45 Figure 1 is a plan of the air gun, partly broken away and partly in section, showing a gun mechanism in a fired or released position;

50 Fig. 2 is a cross sectional view taken on the line II—II of Fig. 1;

Fig. 3 is a side elevation of a portion of the air gun, partly broken away and partly in section, showing the gun loaded and ready to be cocked;

55 Fig. 4 is a cross sectional view taken on the line IV—IV of Fig. 3;

Fig. 5 is an end view of the gun, with the barrel thereof in cross section, and shifted to a loading position, and

Fig. 6 is a longitudinal sectional view of a portion of the gun barrel in a closed position.

In the drawings, the reference numeral 1 denotes the grip portion of a gun stock and suitably connected to this grip portion is a 65 connecting member 2 for a tubular breech piece or spring barrel 3 which has its side walls slotted, as at 4, at the outer end thereof. In the inner end of the breech piece is fixed a sear block or guide 5 for a vertically 70 disposed slidable sear 6, which has its upper end protruding out of the upper face of the breech piece and beveled, as at 7. The sear 6 has openings 8, 9 and 10, the former provided with an adjustable screw plug 11 for 75 regulating the tension of a spring 12 within the opening 9 and on an anchor rod or screw 13 carried by the sear block 5 and extending through the opening 9 of said sear. Extending into the opening 10 of the 80 sear 6 is a trigger 14 pivotally supported, as at 15, by the inner end of the breech piece, said trigger being inclosed by a guard 16 suitably connected to the lower wall of the breech piece and the stock grip 1. The 85 trigger 14 is constantly in engagement with the sear 6 and the sear may be retracted by pulling on the trigger 14. When the trigger 14 is released the expansive force of the spring 12 elevates said sear.

In the forward end of the breech piece or spring barrel 3 is a vertically disposed pivot pin 22 and pivotally mounted on said pivot pin and extending through the side slot 4 of the breech piece are main operating 95 levers 18 and 19 having the outer ends thereof provided with hand grips or handles 20. The inner end of the main lever 18 is forked or bifurcated, as at 21 with the inner end of the main lever 19 extending there-through, and pivotally connected to the inner end of the main levers 18 and 19, as at 22, are links 23 and 24. The links 24 are two in number, as best shown in Fig. 2, so as to provide clearance for the main operating 100 lever 19, and the inner ends of the links 23 and 24 are pivotally connected together by a pin 25 to which is connected the outer convolution of a coiled expansion spring 26 within the tubular breech piece or spring 105 barrel 3, said spring having its inner convolutions 27 gathered about a spherical head 110

28 adjustable on the anchor rod or screw 13. By disconnecting the breech piece from the connecting member 2, the anchor rod or screw 13 may be adjusted to regulate the 5 tension or expansive force of the spring 26 within the breech piece 3.

Suitably fixed to the outer end of the breech piece or spring barrel is a support 29 which extends above the breech piece and 10 has an apertured boss 30 on which is shifted the outer end of an air cylinder or piston barrel 31, said air cylinder having the inner end thereof toothed and supported from the breech piece by a bracket 32. The air 15 cylinder 31 is in spaced relation to the upper wall of the breech piece and slidable between said breech piece and the air cylinder is a slide block 33 which has the forward end thereof provided with apertured ears 34 to 20 which are pivotally connected arms 35 that have the outer ends thereof pivotally connected, as at 36, to the outer ends of the main levers 18 and 19, said arms being curved from the plane of the levers 18 and 19 to the 25 plane of the slide block 33. On the rear end of the slide block 33 is a post 37 extending through a slot 38 in the lower wall of the air cylinder 31, and suitably connected to said post is a piston rod 39 which has a forward end or outer end thereof connected to a 30 piston 40 reciprocable in the air cylinder 31. The piston 40 has a suitable packing ring 41 and the outward stroke of said piston is cushioned by a buffer 42 in the air cylinder 35 against the apertured boss 30, said buffer being apertured similar to said boss.

On the rear end of the slide block 33 is an apertured lug 43 and this lug is adapted to be engaged by the upper beveled end of the 40 sear 6, so that said slide block will be held in a retracted position with the spring 26 expanded.

The cylinder support 29 is provided with a stud bolt or pivot pin 44 for the lower end 45 of a barrel end plate 45 having an integral barrel 46 adapted to register with the apertures in the boss 30 and the buffer 42. The barrel end plate 45 is spring pressed and frictionally held against the cylinder support 50 port 29 by a coiled compression spring 47, and an adjustable nut 48 on the stud bolt 44, and the movement of said barrel end plate relative to the cylinder support 29 is limited by a pin 49, carried by the support 29, 55 tending into a segment slot 50 of the barrel end plate 45, as best shown in Fig. 5. The barrel end plate 45 also has a beveled lug 51 which rides into a recess 52 of the cylinder support 29 and wedges or forces the barrel end plate 45 against the cylinder support 29, 60 as shown in Fig. 6. With the barrel end plate 45 swung to one side, as shown in Fig. 5, a projectile 53 may be placed in the inner end of the barrel 46 and by swinging the barrel end plate to a closed position in 65

registration with the cylinder support 29, the barrel 46 is in position for the air gun to be discharged.

Assuming that the gun is in the position shown in Fig. 1, both hands may be employed on the levers 18 and 19 to pull the outer ends thereof rearwardly and inwardly toward the breech piece of the gun. This movement of the levers 18 and 19 pulls outwardly on the links 23 and 24 causing the 75 spring 26 to be expanded and simultaneous with this operation the block 33 is shifted rearwardly so that the piston 40 will be retracted and the apertured lug 43 snapped into engagement with the slideable sear 6. 80 The gun is now cocked and by pulling on the trigger 14, the sear 6 is retracted or lowered to release the slide block 33, which is forcibly shifted by retraction of the spring 26, through the medium of the levers 18 and 85 19, links 23 and 24 and arms 35. The air in the outer end of the cylinder 31 is forced through the apertured buffer 42 and the boss 30 against the inner end of the projectile 53 and said projectile is ejected from the barrel 90 46.

To prevent the fingers of a hand holding the gun from interfering with the movement of the slide block 33 or being injured thereby, the breech piece has lateral guards 95 54 connected to the sides of the breech piece 3 by screws 55 or other fastening means.

One embodiment of my invention has been illustrated, but it is to be understood that the structural elements are susceptible to such 100 variations and modifications as fall within the scope of the appended claims.

What I claim is:—

1. An air gun comprising a breech piece, an air cylinder on said breech piece, a barrel 105 supported from said breech piece in axial alignment with said air cylinder and adapted to have a projectile inserted in its inner end, air propulsion means in said air cylinder, operating means including opposed levers extending through said breech piece, and means slidable between said breech piece and said air cylinder and connected to the levers of said operating means for operating said air propulsion means. 115

2. An air gun as characterized in claim 1, wherein said operating means includes a spring, and links connecting said spring to the inner ends of the levers of said operating means for placing said spring under 120 tension.

3. An air gun as characterized in claim 1, wherein the barrel is pivotally supported from the breech piece and adapted to be swung out of alignment with the air cylinder 125 so that said barrel may be loaded.

4. In an air gun, the combination with a breech piece, a barrel, and means at said breech adapted for discharging a projectile from said barrel, of a barrel end plate sup- 130

porting said barrel relative to said breech piece and adapted to be swung to one side to permit of said barrel being loaded at the inner end thereof.

5 5. The combination set forth in claim 4, wherein additional means is employed for holding said barrel in a closed position.

6. An air gun comprising a breech piece, an air cylinder on said breech piece, a barrel 10 alining with said air cylinder and adapted for holding a projectile, a piston in said air cylinder adapted to force air against the projectile in said barrel, a slide block between said air cylinder and said breech 15 piece for moving said piston, and means carried by said breech piece adapted for shifting said slide block.

7. An air gun as characterized in claim 6 wherein the barrel is pivoted relative to the 20 breech piece and adapted to be swung to one side to receive the projectile in its inner end.

8. An air gun comprising a breech piece, an air cylinder on said breech piece, a barrel alining with said air cylinder and adapted 25 for holding a projectile, a piston in said air cylinder adapted to force air against the projectile in said barrel, a slide block between said air cylinder and said breech piece for moving said piston, lever mechanism in the 30 outer end of said breech piece adapted to move said slide block, said lever mechanism being manually actuated to move said slide block in one direction, and means in said

breech piece placed in active condition by the manual actuation of said lever mechanism adapted to shift said block in an opposite direction.

9. An air gun as characterized in claim 8 wherein additional means in said breech piece is adapted to hold the last mentioned 40 means in an active condition.

10. An air gun as characterized in claim 8 wherein the barrel is pivoted relative to said breech piece and adapted to be swung to one side to receive the projectile in its 45 inner end.

11. An air gun as characterized in claim 8, wherein the lever mechanism includes pivoted levers protruding from the sides of the breech piece, and arms connecting 50 said levers to said side blocks.

12. The combination with an air gun having a spring actuated piston, of a lever mechanism adapted to simultaneously retract the piston and expand the spring 55 thereof, a slide block articulating said lever mechanism and the piston of said gun, and means adapted to engage said slide block to hold the piston retracted and the spring expanded.

In testimony whereof I affix my signature in the presence of two witnesses.

OTTO SEEMULLER.
